(57) **CLAIM**

The ornamental design for a door fastener, as shown and described.

DESCRIPTION

FIG. 1 is a front and top perspective view of a door fastener, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in a using position; and,

FIG. 10 is another perspective view thereof, shown in another using position.

The broken lines in the figures illustrate portions of the door fastener that form no part of the claimed design. The broken lines showing of a portiere in FIG. 9 and 10 depict environmental structure that form no part of the claimed design.

1 Claim, 10 Drawing Sheets
